PAGE 2

FIG. 2

FIG. 3

FIG. 4

FIG. 5

FIG. 6

FIG. 1 is a side elevation of a gas lighter for cigarettes and the like, showing my new design, the opposite side being substantially the same;

FIG. 2 is an elevation thereof as seen from the left of FIG. 1;

FIG. 3 is an elevation thereof as seen from the right of FIG. 1;

FIG. 4 is a top plan view thereof;

FIG. 5 is a bottom plan view thereof;

FIG. 6 is a perspective view as seen from the front and side thereof.

It is to be understood that the vertically arranged perforations on the decorative panel on the front of the lighter are uniformly spaced along the length of the horizontally aligned bands as best indicated in FIG. 1.

I claim:

The ornamental design for a gas lighter for cigarettes and the like, substantially as shown and described.
